DEHAIRING DEVICE

John Gonsor, Chicago, Ill.

Application August 5, 1938, Serial No. 223,170

7 Claims. (Cl. 17—18)

The present invention relates to dehairing devices and has for its main object the provision of a dehairing device to be employed for dehairing hog carcasses.

5 A still further object of the present invention is the provision of a dehairing device which may include a plurality of cleaning elements and a plurality of scraping elements arranged in an alternate relation, said elements being arranged 10 in a substantially radial formation and suitably mounted within a round rotatable frame structure to adapt them to rotate therewith for the purpose of scraping, cleaning and removing hair from a carcass.

15 A still further object of the present invention is the provision of a dehairing machine of the character indicated and in which the scraping and cleaning elements may remain under a uniform and constant steam pressure tending to 20 maintain them in an extended position, with means provided whereby said cleaning and scraping elements may yield against the steam pressure when the same come in contact with the body of the carcass.

25 A still further object of the present invention is the provision of a suitable mechanism for utilizing steam for the objects hereinabove set forth.

With the above general objects in view and others that will appear as the invention is better understood, the same consists in the novel construction, combination and arrangement of parts hereinafter more fully described, illustrated 30 in the accompanying drawings and pointed out in the appended claims.

35 In the drawings forming a part of this application, and in which like designating characters refer to corresponding parts throughout the several views;

Fig. 1 is a side elevational view, partly in section, of the present device;

40 Fig. 2 is a cross-sectional view, partly in elevation along and through line 2—2 of Fig. 1;

Fig. 3 is an elevational view on a reduced scale, taken from the opposite side of the device, the 45 view illustrating the position of the device with relation to an animal carcass;

Fig. 4 is an edge elevational view of the device;

Fig. 5 is a diametrical cross-sectional view 50 through the annular frame structure within which the mechanism of the device is adapted for mounting;

Fig. 6 is a cross-sectional view on an enlarged scale of a steam pipe connection with a cylindrical shaft upon which the frame is mounted; and

Fig. 7 is a perspective view on an enlarged scale of a mounting plate constituting a part of the mechanism of the present device.

Referring to the present drawings in detail there is shown therein a cylindrical shaft 10 with which steam pipe 11 connects. Said steam pipe 11 at one of its ends is provided with a radially projecting annular flange 12 which fits within and contacts with the inner periphery of the enlarged end bore 13 of said cylindrical shaft 10, and rests upon gasket 14 which rests upon a resulting shoulder at one end of said enlarged bore 13 as is clearly seen in Fig. 6. On the opposite side of said flange 12 and between the outer periphery of steam pipe 11 and inner periphery of bore 13, packing 15 is stuffed which is maintained in its position by an annular boss 16 through which said steam pipe 11 extends. Said annular boss 16 has an annular projecting flange 17 through which a number of screws 18 extend, the latter engaging the adjacent end of said cylindrical shaft 10. Nuts 19 provided at the outer ends of said screws 18 and bearing against said flange 17, constitute means for maintaining said boss 16 in an adjusted position 25 within bore 13.

The device further includes a circular lateral wall plate 20 which carries centrally projecting therefrom and integrally formed therewith a hub extension 21 through which said cylindrical shaft 10 extends and to which said cylindrical hub extension 21 is keyed by means of an oblong key 22 entering into the adjacent body portion of said cylindrical hub extension 21 and a corresponding key slot 23 made in said cylindrical shaft 10, as is clearly seen in Figs. 1 and 5. By virtue of this arrangement cylindrical hub 21 including its circular side wall 20 will be prevented from making rotary movement independently of said cylindrical shaft 10. To 30 maintain the device from making longitudinal movement upon said cylindrical shaft 10, a screw 24 may be provided at one point of said cylindrical hub extension 21 which may extend therethrough and engage said cylindrical shaft 10, as 35 is seen in Fig. 1.

Said circular lateral wall plate 20 is provided at its outer portion with an integrally formed annular flange 25, and at a meeting line between said circular lateral wall plate 20 and said annular flange 25, an annular, integrally formed and outwardly projecting manifold 26 is provided. An adjustable connecting pipe 27 is provided for connecting cylindrical shaft 10 with said annular manifold 26. Integrally formed 50

with said manifold 26 and at the outer face of said circular lateral wall plate 20 are four inwardly extending and substantially radially arranged branch pipes 28. Said circular side wall 5 20 is provided with outlet openings 29 with which said branch pipes 28 communicate.

The mounting plate best shown in Fig. 7, includes a vertical plate 30, from the bottom edge of which a pair of oppositely disposed wing plates 10 31 and 32 project. Said wing plates 31 and 32 are affixed to the inner face of circular lateral wall plate 20 by means of a plurality of bolt screws 33 which extend through screw openings 15 34 made in said wing plates 31 and 32 and corresponding aligned openings in circular side plate 20. Interposed, however, between the inner face of said circular side plate 20 and the adjacent inner faces of wing plates 31 and 32 are gaskets 35 which have openings aligned with screw openings 34 as well as openings in alignment 20 with outlet openings 29.

The vertical portion 30 of said mounting plate is provided with a plurality of screw openings 36 for the purpose hereinafter stated and with an 25 integrally formed pipe 37 which communicates with a transverse vent 38 made in said vertical plate 30.

The device further includes four steam cylinders 39 one affixed to each of said vertical plates 30 and to the side thereof which is adjacent to wing plate 32. Each of said cylinders has a lateral and longitudinal extension 40 from which base plate 41 projects. Said base plate 41 is provided with a plurality of aligned screw openings 35 corresponding to screw openings 36 by means of which each of said cylinders 39 is affixed to said vertical plate 30 by means of a corresponding plurality of screws 42. Interposed between said vertical plate 30 and cylinder plate 41 is a gasket 43 and cylinder plate 41 is provided with an oblong opening 44 made longitudinally of said base plate 41 and adjacent one of its ends, which opening 44 communicates with vent 45 made in said cylinder 39. Each of said cylinders 39 has a closed end 46 and through the other open end it receives piston 47. Vent 45 is disposed adjacent end 46 of cylinder 39.

By virtue of the construction heretofore explained steam fed from steam pipe 11 is led to all cylinders 39 through cylindrical shaft 10, connecting pipe 37, manifold 26, branch pipes 28, outlet openings 29, pipes 31, vents 38, openings 44 and vents 45, and also through openings in gaskets 35 and 43.

The outer end of said piston 47 is provided with a bearing head 48, which in its length equals to the diameter of cylinder 39, with the resultant end lugs 49 which are set within a pair of oblong recesses 50 made longitudinally of each cylinder 39 and adjacent the open end of each cylinder 39. Thus said end lugs 49, being set within said recesses 50 constitute means for uniformly guiding each of said pistons 47 in its longitudinal shifting movement within cylinder 39. Received 60 within each of said piston bearing heads 48 is shaft 51, the ends of which extend beyond lugs 49 and pass through and engage heads 52 of a pair of levers 53. Said heads 52 are provided with transverse recesses 54 wherein cotter pins 55 65 passing through the outer ends of each shaft 51, are adapted for positioning, as is clearly seen in Figs. 1 and 2.

The opposite ends of each pair of said levers 53 are likewise provided with similar recessed heads 56 which are engaged by shafts 57 which

pass through the adjacent enlarged ends of rocker bars 58. Said shafts 57 are maintained in position by means of cotter pins 59 positioned within said recessed heads 56.

Said circular side wall 20 is provided at its inner face with an integrally formed annular wall 60, which is provided at its free end with an integral and outwardly extending rim flange 61, which diametrically is co-extensive with flange 25. Said flanges 25 and 61 are provided with opposed pairs of inwardly projecting sockets 62. Said flanges 25 and 61 are in a concentric relation with respect to the longitudinal axis of cylindrical shaft 10, and all sockets 62 are at the same distance from shaft 10.

Each of said rocker bars 58 is provided adjacent its central portion with a transverse lateral extension 63 for receiving therethrough shaft 64 the ends of which being positioned within a pair of said sockets 62. Each of said shafts 64 is keyed 20 to each pair of said sockets 62 by means of screws 65 passing through screw openings 66 made in each socket 62. Rocker bar 58 is positioned upon shaft 64 for free pivotal movement, and each shaft 64 is rigidly affixed to sockets 62 by means 25 of screws 65. Each pair of diametrically, oppositely disposed rocker bars 58 is adapted to receive a scraping device which includes a base plate 67 including its free inner end portion 68 by means of which said base plate 67 is affixed to 30 the free outer end of rocker bar 58 and by means of a pair of screw bolts 69. Said base plate 67 is in an angular relation with its end portions 68 in one direction, being the direction away from the carcass when said scraping devices are in 35 an operative position with its hide. Integrally formed with each of said base plates 67 is a pair of lateral plates 70, which are in an angular relation with base plate 67 and which project from said base plate 67 in one same direction.

Affixed by means of rivets 71 to said plates 70 is a pair of scraping plates 72, which at their free edges are provided with indentations 73 for the purpose of permitting continual flow of water as said scraping plates 72 come in contact with the 45 hide of the carcass, thereby preventing complete wiping of the water from the carcass hide as said scraping plates 72 come in contact therewith. Otherwise, drying of the carcass hide would ensue which in consequence might injure the hide 50 as said scraping plates 72 come in contact therewith. Said indentations 73 are arranged alternately in two plates 72.

Each of the other pair of diametrically disposed free ends of rocker bar 58 is adapted to receive 55 a mounting plate 73 and a superimposed brush carrying plate 74, the two plates by their inner ends being affixed to the outer free end of each rocker bar 58 by means of screw bolt connection 75. Both of said plates 73 and 74, and substantially at the meeting line thereof with the outermost termination of rocker bar 58, are bent in one direction which is the direction disposed away from the body of the carcass as the brush devices come in contact therewith. Said brush carrying plates 74 have brushes 76, and to maintain said brushes 76 in rigid position, said brush carrying plates 74 are affixed to said mounting plates 73 by means of screws 77.

At points adjacent which rocker bars 58 project through annular wall 60 the same is provided with enlarged openings 78, permitting an unobstructed swinging motion and shifting of said rocker bars 58 and of levers 53 as the cleaning and brushing devices make angular swinging mo- 75

tion upon pivots 64 as they come in contact with the carcass hide. Made in annular wall 60 and in an alternate relation with said openings 78 are circular openings 79 for permitting flushing of the water as well as falling out of the hair which may find itself within said annular wall 60. For analogous purpose a number of circular openings 30 is made in the side wall 20.

It is observed that opening 44 is made oblong so as to assure an unimpeded passage of steam therethrough from vent 38 and into vent 45 and into cylinder 39 through the latter, regardless that vents 38 and 45 may not be in proper alignment due to some possible imperfection of alignment base plate 41 with plate 30 and their respective vent openings 38 and 45.

Assuming that there is a uniform supply of steam to cylinders 39 through various pipe connections and vents hereinabove described, the steam in each cylinder 39, pressing upon the adjacent end of piston 47, will urge said piston outwardly and maintain the same in an extended position illustrated in the cross-sectional portions of Figs. 1 and 2. In that position end lugs 49 of piston bearing head 48 will remain within the outer ends of recesses 50, which in turn will maintain levers 53 in parallel relation with their respective cylinders 39. This position of levers 53 will in turn maintain rocker bars 58 in an extended position substantially co-extensive with the longitudinal axis of each cylinder 39 and in a substantially radial position with respect to circular side wall 20, as is seen in full lines in Fig. 1. This position of rocker bars 58 will in turn maintain the scraping and brush devices in an extended position shown in full lines in Figs. 1 and 3.

When said scraping and brush devices shall come in contact with the carcass hide during process of dehairing the same, the contacting pressure exerted upon said scraping and brush devices will tend to shift the same angularly upon their pivots 64 to assume a range of angular positions which are intermediate between the position of said scraping and brush devices shown in full lines and illustrated in dotted lines in Fig. 1. When said scraping and brush devices are angularly shifted upon their respective shafts 64 rocker bar 58 by its inner end will be shifted outwardly of annular wall 60 and through its respective opening 78 to assume the position shown in dotted lines in Fig. 1. This angular shifting movement of the inner end of rocker bar 58 will in turn shift levers 53 both lengthwise and angularly with respect of their respective cylinders 39, which shifting movement of said levers 53 will in turn shift piston 47 against the steam pressure within cylinder 39. It should be noted, however, that piston 47 in its inwardly extended position within cylinder 39 at no time closes vent 45, but reaches to about one-half of its area so as to assure constant presence as well as constant supply of steam into the cylinder. When contacting pressure at said scraping and brush devices is released, the same automatically tend to shift to their extended positions due to the pressure of steam within cylinder 39 exerted upon piston 47.

When the dehairing device herein described is brought quite close to the carcass hide, and the same rotates, scraping plates 72 in each scraping device will both simultaneously contact the hide for exerting pulling pressure upon the hair, while said scraping device passes past the carcass hide and remains in an angularly shifted position.

Likewise brushes 76 contact by their entire faces the carcass hide when the brush devices shift past the carcass hide and are angularly shifted as they come in contact therewith, assuming the position shown in Fig. 3, the carcass being indicated by dotted lines and marked by 76'.

To rotate the entire dehairing device bodily including circular side wall 20 and annular wall 60, and to bodily rotatably shift scraping and brush devices, together with cylindrical shaft 10, a suitable mechanism may be used, such as belt connection from a source of power or gear connection therewith. Since it is not only desirable but necessary to bring the dehairing device close to the carcass the same, including cylindrical shaft 10 must have a rotatable yieldable connection with steam pipe 11, which may include a universal joint, swivel or any other suitable connection.

While there is described herein a preferred embodiment of the present invention, it is nevertheless to be understood that minor changes may be made therein without departing from the spirit and scope of the invention as claimed.

What I claim as new is:

1. A dehairing device comprising a frame, a hide contacting element pivotally mounted in said frame, for permitting said element to make angular shifting movement as the same comes in contact with the hide, a cylinder mounted in said frame, a piston in said cylinder, said cylinder being adapted to receive a constant supply of fluid, and connecting means between said piston and said hide contacting element, said connecting means being adapted to maintain said hide contacting element in an extended position upon its pivot, said fluid being adapted to shift said piston for the purpose of urging said connecting means for bringing said hide contacting element from its angular position into its extended position.

2. A dehairing device comprising a rotatable frame, a plurality of dehairing elements pivotally mounted in said frame and adapted to revolve with the frame as the same rotates, said dehairing elements being arranged to swing outwardly to an extended hide engaging position and to angularly shift upon their pivots to a retracted position when coming in contact with the hide, and pneumatic means for normally urging said dehairing elements to assume such extended position.

3. A dehairing machine comprising a rotatable circular frame, a plurality of hide contacting elements pivotally mounted in said frame, said elements remaining normally in extended positions upon their respective pivots, said elements being adapted to angularly shift when the same come in contact with the hide during the rotation of said frame, means for urging said elements to assume their normal extended positions from their angular positions, said means including cylinders adapted to receive a constant and uniform supply of fluid, pistons within said cylinders, and pivotal connecting means between said pistons and said elements.

4. A dehairing machine comprising a shaft, a circular wall mounted upon said shaft, an annular wall integrally formed with said circular wall, in an angular relation with said circular wall and in a concentric relation with said shaft, parallel and integrally formed flanges extending from said circular wall and said annular wall, a plurality of hide contacting elements pivotally mounted within said flanges, means for main-

taining said hide contacting elements in an extended and substantially radial position with respect to said circular wall, said hide contacting elements being adapted to angularly shift as they come in contact with the hide, and pneumatic means for bringing said hide contacting elements into their normal extended position when said elements come out of contact with the hide.

5. In a dehairing machine, a rotatable shaft, 10 a frame rigidly secured thereon, hide contacting elements pivoted to the frame, cylinders carried by the frame, pistons reciprocable in said cylinders, each of said pistons being connected with one of said hide contacting elements, and means 15 to place said cylinders in constant communication with a source of supply of fluid under pressure.

6. In a dehairing machine, a rotary carrier, a plurality of retractable arms, hide contacting elements carried by said arms, said arms being pivotally mounted on the carrier, and fluid pressure operated means for swinging said arms to normal projected hide engaging position.

7. In a dehairing machine, a hollow rotatable shaft, means to place said hollow shaft in communication with a source of supply of fluid under pressure, a frame rigidly secured on said shaft, 10 hide contacting elements pivoted to the frame, fluid pressure operated means for swinging said hide contacting elements to normal projected hide engaging position, and means to place said fluid pressure operated means in constant communication with said hollow shaft.

JOHN GONSOR.
